TORPEDO ARRESTOR OR INSULATOR

Sidney D. Redmond and Admiral H. McCoy,
Jackson, Miss.

Application June 2, 1942, Serial No. 445,498

5 Claims. (Cl. 114—240)

This invention relates to a torpedo or mine arrester for a vessel.

An object of this invention is to provide an arrester of this kind which is adapted to be positioned on the sides of the vessel and normally disposed out of the water so that it will not impair the normal speed of the vessel, the device being capable of being quickly lowered to an operative and protective position.

Another object of this invention is to provide a device of this kind which is so constructed that it will prevent the torpedo from contacting with the vessel.

A further object of this invention is to provide a protective device of this kind which is so constructed that it will be capable of resisting the impact of the torpedo before explosion of the latter and will so engage the torpedo that it will not explode.

A further object of this invention is to provide a protective device in the form of a fibrous screen which is mounted in a metal frame, the frame providing sufficient weight to maintain the screen at the desired depth in the water, and sufficient strength to permit the screen to withstand the shock of impact of a torpedo therewith.

A further object of this invention is to provide a protective screen which is formed of interlaced fibrous strands, the crossing points of the strands being firmly locked together and the interstices between the strands being of such size as to permit at least a portion of the torpedo nose to engage therein, but being small enough to prevent a torpedo from passing therethrough.

With the foregoing objects and others which may hereinafter appear the invention consists of the novel construction, combination and arrangement of parts as will be more specifically referred to and as illustrated in the accompanying drawing wherein is shown an embodiment of the invention, but it is to be understood that changes, variations and modifications may be resorted to which fall within the scope of the invention as claimed.

In the drawing:

Figure 1 is a fragmentary side elevation of a vessel having a torpedo arrester or protector mounted thereon,

Figure 2 is a sectional view taken on the line 2—2 of Figure 1, and

Figure 3 is a fragmentary side elevation of the torpedo arresting or protecting screen.

Referring to the drawing, the character V designates generally a vessel of suitable construction and the numeral 10 designates generally a torpedo protecting screen which is disposed in outstanding position with respect to the side 11 of the vessel. The screen or protecting member 10 comprises a rectangular metal frame 12 which has secured to the inner side thereof a plurality

of spaced apart eyes 13 which are extended outwardly through openings 14 formed in the frame 12 and the outer ends of the eyes 13 are upset as at 15.

5 A plurality of vertically spaced horizontal fibrous strands 16 are secured to the eyes 13. The strands 16 are preferably formed out of rope or other flexible material and the opposite ends of each horizontal strand 16 are formed with a 10 loop or reverted portion 17. The adjacent reverted end of the strand 16 is spliced or otherwise secured as at 18 so that the eye 13 will be enclosed in the reverted portion 17. The screen structure 10 also includes a plurality of horizontally spaced apart vertical strands 19 which are adapted to be secured at their upper and lower ends to upper and lower eyes 13. The opposite ends of the vertical strands 19 are reverted as at 20 and then secured or spliced as at 21. At 15 the points where the horizontal and vertical strands 16 and 19 respectively cross each other, the strands 16 and 19 are tied or locked together by means of a locking strand 22. The interstices formed by the strands 16 and 19 are of such a size 20 that the nose of a torpedo may engage therein but the complete torpedo will be prevented from 25 passing through the screen and in this manner the torpedo will be held against exploding.

The frame member 12 is held in outstanding 30 relation with respect to the side 11 of the vessel when in operative position by means of a pair of right angularly disposed supporting bars 23. The bars 23 at their outer ends are secured to the upper horizontal bar 24 of the frame 12 and the bars 23 at their inner ends are secured to a 35 lengthwise extending bar 25. A pair of hinge members 26 are secured to the longitudinal bar 25 and each hinge member 26 has one leaf 27 thereof secured as by fastening means 28 to the 40 outer side of the vessel side wall 11.

The upper frame bar 24 has fixed thereto a 45 pair of spaced apart eyes 29 and one end of an elevating flexible member 30 is secured to the eye 29. The flexible member 30 is extended through a sheave 31 which is secured as by an eye or fastening member 32 to the side 11 of the vessel adjacent the upper edge of the rail thereof. The flexible elevating member 30 may then be extended inwardly of the upper deck of the 50 vessel and engaged with a winch or other elevating and lowering means so that the protecting screen 10 may be normally disposed in an uppermost position out of engagement or contact with the water and may be easily and quickly lowered to substantially submerged position 55 in the water as shown in Figure 2.

In order to provide a means whereby the protecting member 10 may be supported in an operative position with the bars 23 horizontal and the protecting member 10 vertical, we have pro-

vided a pair of flexible supporting members 33 which are secured as at 34 to the upper frame bar 24. The side 11 of the vessel is provided with a pair of hooks 35 with which the chain or flexible member 33 is adapted to be engaged.

In the use of this protecting device or torpedo arrester, the device is secured by means of the hinge members 26 to the side of the vessel closely adjacent the waterline. The flexible members 30 are then engaged with one or more winches or elevating and lowering devices and during the normal operation of the vessel V the protecting member 10 will be elevated and the bars 23 disposed in substantially a vertical position. In this manner, the protecting member 10 will not impair the speed of the vessel during normal operation.

In the event a torpedo is sighted or the vessel V enters a dangerous zone the protecting member 10 may be lowered to the limit permitted by the flexible supporting members 33. Under certain conditions, the protecting member 10 may be disposed in a substantially vertical position which is the position shown in full lines in Figure 2. In this vertical position the lower edge of the protecting member 10 will be disposed substantially coplanar with the bottom of the vessel. However, if desired, the protecting member 10 may be lowered to the position shown in dotted lines in Figure 2 so that the protecting member 10 will be disposed at an angle to the vertical and the lower edge thereof will be disposed below the bottom of the vessel. In this latter position, the protecting member 10 will be disposed at an oblique angle to the movement of a torpedo towards the vessel so that in this oblique angle the protecting member or arrester 10 will tend to deflect any torpedoes which may strike it.

In the event a torpedo should strike the screen or protecting member 10 in such a manner as to explode the torpedo, this explosion will not cause as great damage to the vessel V as would be caused if the torpedo struck the side of the vessel. There may be as many of these protecting devices as may be desired about the exterior of the vessel V and the screen formed by the interlacing and intersecting strands 16 and 19 may be formed out of rope or other like material which is of sufficient strength to withstand the shock from the impact of the moving torpedo.

What we claim is:

1. A protecting screen for a vessel comprising a frame structure, means pivotally supporting said frame structure on the side of a vessel for movement from an inoperative position above the waterline to an operative position within the water, means limiting the downward swinging movement of said frame, means for elevating or lowering said frame, interlaced fibrous strands carried by said frame, the interstices between said strands being sufficiently large to admit entrance of the nose of a torpedo and locking strands securing said interlaced strands together at the points of intersection.

2. A protecting screen for a vessel comprising a frame structure, means pivotally supporting said frame structure on the side of a vessel for movement from an inoperative position above the waterline to an operative position within the water, means limiting the downward swinging movement of said frame, means for elevating or

lowering said frame, a plurality of horizontally disposed spaced apart parallel fibrous strands fixed in said frame, a plurality of vertically disposed spaced apart parallel fibrous strands to thereby form a fibrous screen having interstices sufficiently large to receive the nose of a torpedo and locking strands securing said horizontal and vertical strands together at the points of intersection.

3. A protecting screen for a vessel comprising a frame structure, right angularly disposed bars fixed at their outer ends to the upper portion of said frame and extending inwardly therefrom, means engaging the inner ends of said bars pivotally supporting said frame structure on the side of a vessel for movement from an inoperative position above the waterline to an operative position within the water, means limiting the downward swinging movement of said frame, means for elevating or lowering said frame, a plurality of inwardly projecting eyes carried by said frame, a plurality of horizontal spaced apart parallel fibrous strands secured to certain of said eyes, and a plurality of vertically disposed spaced apart fibrous strands interlaced with said horizontal strands and fixed to certain others of said eyes.

4. A protecting screen for a vessel comprising a frame structure, right angularly disposed bars fixed at their outer ends to the upper portion of said frame and extending inwardly therefrom, means engaging the inner ends of said bars pivotally supporting said frame structure on the side of a vessel for movement from an inoperative position above the waterline to an operative position within the water, means limiting the downward swinging movement of said frame, means for elevating or lowering said frame, a plurality of inwardly projecting eyes carried by said frame, a plurality of horizontal spaced apart parallel fibrous strands secured to certain of said eyes, a plurality of vertically disposed spaced apart fibrous strands interlaced with said horizontal strands and fixed to certain others of said eyes, and means engaging about said horizontal and vertical strands at the points of crossing of said strands for holding one strand against shifting lengthwise of an adjacent strand.

5. A protecting screen for a vessel comprising a frame structure, right angularly disposed bars fixed at their outer ends to the upper portion of said frame and extending inwardly therefrom, means engaging the inner ends of said bars pivotally supporting said frame structure on the side of a vessel for movement from an inoperative position above the waterline to an operative position within the water, means limiting the downward swinging movement of said frame, means for elevating or lowering said frame, a plurality of inwardly projecting eyes carried by said frame, a plurality of horizontal spaced apart parallel fibrous strands secured to certain of said eyes, a plurality of vertically disposed spaced apart fibrous strands interlaced with said horizontal strands and fixed to certain others of said eyes, and a flexible locking strand engaging about said horizontal and vertical strands at the points of crossing thereof for locking the horizontal and vertical strands against shifting relative to each other.
